To all whom it may concern:

Be it known that George W. Fig. 4 is a plan view of the same.

This application is a continuation in part of my application for Vacuum cleaner casing, Serial No. D-109,933, filed April 17, 1943.

The design of a vacuum cleaner casing embodying my invention is such that the casing at the sides and front is relatively low and flat and slopes inwardly and upwardly into a hood portion which is positioned centrally of the casing toward the back thereof.

The essential features of my design are shown in full lines on the drawing.

I claim:
